SUBMINIATURE CONNECTOR FOR
COAXIAL CABLESAlbert E. Powell, Old Greenwich, Conn., assignor to
Micron Electronics, Inc., Garden City, Long Island,
N.Y.Filed Jan. 24, 1962, Ser. No. 168,397
2 Claims. (Cl. 339—177)

The present invention relates to improved coupling means for use with coaxial cables and more particularly to coaxial cables of minimal dimensions wherein the outer conductor is of solid metal, in contradistinction to braided outer conductors in coaxial cables.

The growth of the field of subminiaturization, involving the use of components verging on the microscopic, raises problems not anticipated in conventional electronic components, even as to those which can loosely be called "subminiaturized." Thus, in the art of providing connectors for coaxial cables it is well known to provide coupling means for cables having an outer conductor of braided or woven conductor material, usually copper. Generally speaking, the flexible outer braid is separated from the insulator layer and physically clamped to the connector. However, the need for miniaturization has created a demand for coaxial cable of such small dimension that a layer of metal a few thousandths of an inch thick is deposited over the insulator layer to form the outer conductor; hence it is manifestly impossible to separate the outer metallic layer from the insulator without destruction of the cable itself. It may be added that the need for subminiature cables is so great that it has been necessary to develop new manufacturing techniques to apply an outer conductive layer of copper so thin that an added coating of lead has to be applied about this to provide structural solidity, to prevent the copper layer from being rubbed off or otherwise removed. It will therefore be apparent that radically different means must be employed to form a connector for cable of this type, and means applicable for a braided type coaxial cable are not suitable.

The design of a subminiaturized device is necessarily dependent on the state of the art of manufacturing the individual components involved, and the techniques presently available. As the device of this invention is described hereinafter, it will be appreciated that the simple, axial "plug in" mating configuration employed is far more desirable than the use of a threaded engagement. The machining of extremely fine screw threads is costly and subject to a high rate of production rejects. The fragile fine screw type couplings are subject to the stripping of threads and have the added drawback of twisting the individual cables during connection or dismantling, with attendant risk of rupturing the connections. The present device envisages an extremely simple snap connection with the use of detents, whereby the device is brought together in the assembled condition by translational movement rather than by twisting of the cables. The present embodiment of the invention employs a thread only for the original assembly of connector to cable, hence the thread is used only once. For operational use, there is provided a simple connection of maximum reliability, as set forth hereinbelow.

It is therefore a primary object of the present invention to provide an improved connector for subminiature coaxial cables of the solid outer conductor type.

It is a further object of the present invention to provide connector means having simplified means for manufacture and assembly, and having maximum freedom from failure or disconnect, consonant with small physical size.

It is a particular object of the present invention to provide connector means where there is no lateral deforma-

2

tion of the cable elements, wherein clamping, flaring, compression or other physical tampering with the cable is avoided.

Other objects and advantages of the present invention will be apparent or will be pointed out with greater particularity in the following description taken in conjunction with the accompanying drawings wherein:

FIG. 1 is a perspective full size showing of the connector.

FIG. 1a is a perspective similar view to FIG. 1, but enlarged about ten times.

FIG. 2 is an enlarged cross-section taken along line 2—2 of FIG. 1a.

FIG. 3 is an exploded view of the device.

Referring more particularly to the drawings, there is shown in FIG. 1 an embodiment of the present invention characterized generally by the numeral 10, wherein means are provided for connecting terminal portions to coaxial cables 12 and 14. These cables comprise an inner conductor 16, a plastic insulation 17, such as Teflon or the like, formed about this inner conductor, and an outer conductor 18 of a solid metallic conductor material, as distinguished from the braided outer construction of the usual coaxial cable. It should be noted that it is envisaged that the connector of the present invention be employed with coaxial cables of minimal dimension, wherein the inner conductor has a diameter of 0.008 inch to 0.011 inch and the outer conductor ranges in diameter from 0.025 inch to 0.032 inch. The outer conductor is usually a copper layer formed by being drawn over the insulator during the extrusion of the insulator, with a gold film plated above the copper, or by plating a copper layer over the plastic with a lead protective outer covering, providing relative flexibility to the cable.

Such cable can be provided with an external layer of insulation where desired, but for purposes of illustration this is not shown in the present embodiment.

The connecting means envisaged in the present invention may be broadly characterized as an assembly for providing means for axially mating the inner conductors, means for coaxially mating the inner insulators, and means for coaxially mating the outer conductors, to provide the proper impedance match between the two cables, 12, 14. Such a connector preserves the configuration of a conductive central portion, provided here by contacts 20a-20b. An insulator portion concentric with this is formed by insulators 24a, 24b, 26a, 26b. An outer conductive shell is formed by metallic sleeves 28a-28b and connectors 30a-30b. It will be noted that the coaxial configuration of these elements provide an optimum impedance match for the two coaxial cables that are to be connected.

The outer conductor connecting means comprise metal sleeves 28a-28b, provided with axial bores 30 of a diameter corresponding to that of the outer conductor 18 of the cables. These sleeves are soldered over the end portions of the cables 12 and 14, respectively, hole 31 being provided for inspection purposes. Sleeves 28a-28b have externally threaded end portions 32 adapted to threadedly engage connector portions 30a-30b, each of which is provided with an internally threaded end portion 34. It will be noted that sleeves 28a-28b are provided with a reduced bore portion 29a-29b defining inner shoulders 41. These shoulders abut against the trimmed portion of outer conductor 18, and the reduced bores register with insulation 17 of each cable, respectively. Connectors 30a-30b have an overlapping mating configuration, being retained in the assembled position by split ring 36, whereby female member 30b has a reduced shell portion 38 which abuts with the corresponding undercut segment 40 of the connector 30a. The split ring is assembled in the usual manner. That is, a small amount of clearance is provided between the I.D. of split ring

36 and the annular groove of member 30a in which the ring is seated. When member 30b is assembled the ring is compressed, taking up the clearance, and then allowed to snap back into an opposing groove in member 30b. Thus the split ring is simultaneously engaged in the two opposed grooves thereby preventing relative axial motion between members 30a and 30b. In the assembled condition, connectors 30a-b define a hollow cylindrical member having bore 42. Within this bore are concentrically retained the insulators and contacts, in a manner to be described hereinbelow. Insulators 24a-24b are each provided with an axial bore 43 corresponding to the diameter of the inner insulation 17 of cables 12, 14. An internal shoulder 41 is formed at the ends of metal sleeves 28a-28b to register with a shoulders 31a-31b formed by the juncture of cable insulation 17 and cable outer conductor 18.

Insulators 24a-24b have diameters corresponding to that of bore 42 formed by connectors 30a-30b, and are formed with an external shoulder 46 and collar 43. These register in mating axial configuration with insulators 26a-26b, each of which has a cylindrically hollow end portion 50 adapted to seat on collars 43 and abut shoulders 46 respectively. Insulator 26a is of cylindrical hollow configuration provided with an inner radial flange 52 abutting axially with outer flange 53 formed on contact 20a and is of outer diameter corresponding to that of bore 42. Insulator 26b is of stepped cylindrical configuration having an external wall portion 54 formed of diameter to register with bore 42, and shoulder 55 registering axially with inner flange 56 formed on metal connector 30b. Reduced external wall portion 58 of insulator 26b is adapted to abut inner bore 60 of insulator 24a being retained axially by internal ridge 52 formed on insulator 24a. It will thus be noted that the general overall configuration of insulators 24a-24b and 26a-26b is that of a hollow cylindrical member being retained against axial displacement by the mating configuration of the separate insulators and against lateral displacement by the outer metal shells 30a-30b.

Contact members 20a and 20b are of mating configuration and are connected respectively to the inner conductors 16 of cables 12, 14, by means of axial passages 62 formed in each contact, in which the respective inner conductors 16 are soldered, hole 64 being conveniently formed for inspection (see FIG. 3). In the assembled position, FIG. 1, contacts 20a and 20b registered in mating relation, being retained against axial displacement by the configuration of the insulators disposed concentrically about them. Thus, it will be noted that shoulder 68 of contact member 20a abuts collar 48 of insulator 24a and shoulder 70 of contact 20a abuts inner radial flange 52 of insulator 26a. Similarly, shoulder 72 of contact 20b abuts collar 48 of insulator 24b and shoulder 74 of contact 20b abuts internal shoulder 76 formed on insulator 26b. It will also be observed that contacts 20a-20b are constrained against lateral or transverse movement by the internal diameter configuration of insulators 24a-24b, 26a-26b. Thus, the central outer wall portion 53 of contacts 20a-20b abut the inner walls 80, 80' of insulators 26a and 26b, respectively, and reduced wall portions 82 of contacts 20a-20b register with the bore 43 of insulators 24a-24b, respectively. It will thus be apparent that these contact members are captured against lateral and axial displacement.

In assembling the device of the present invention, a portion of the solid outer conductor 18 of the cable is trimmed away, exposing a terminal or end portion of the insulation 17. Metal sleeves 28a-28b are first soldered onto outer conductors 18, inspection opening 31 being provided in the sleeve for checking the soldering. It will be noted that reduced diameter 29a-29b of sleeve 28a-28b, gives a positive location for the end of the coaxial outer conductor, namely at shoulder 31a-31b, also pro-

viding by its precision bore for the carry over from the coaxial cable to the connector for maintenance of impedance at this point. Insulators 24a-24b are then disposed abutting the respective end section of each metal sleeve, and in contact with the exposed insulation portion of the cable. Next, the contact members 20a and 20b are placed in position, with each of the inner conductors 16 being placed in passage 62 of the contact members respectively, which are then soldered, utilizing inspection openings 64 for checking purposes. Insulators 26a-26b are placed in position respectively about contacts 20a-20b, abutting against these contacts and against insulators 24a-24b, as explained heretofore, in retaining configuration. Outer connector shells 30a-30b are then screwed into position over metal sleeves 28a-28b, respectively, by means of internal threads 34 in registry with external threads 32 of the metal sleeves. In the assembled position, rim 85 of connector 30a retains the end portion of insulator 26a and similarly, internal flange 56 of connector 30b retains insulator 26b by bearing against shoulder 54. The device is then connected by simple axial movement, whereby prong 84 of contact 20a is engaged in receptacle 86 of contact 20b, and simultaneously members 40 and 38 of connectors 30a-30b register, being clamped securely by the action of split ring 36. It will be noted that the device of the present invention provides a connector device wherein none of the components of the cables has been subject to any axial or lateral distortion, that there has been no crimping, pressure, or compression on any of the conductors of the insulator of the coaxial cables. Moreover, due to the minute dimensions of the parts involved, it will be apparent that the simple snap feature will provide trouble-free operation where the use of a threaded collar to join the two sections would prove impractical in the present instance.

There has been disclosed heretofore the best embodiment of the invention presently contemplated and it is to be understood that various changes and modifications may be made by those skilled in the art without departing from the spirit of the invention.

What is claimed is:

1. A subminiature assembly for releasably connecting first and second coaxial cables each of which has an inner conductor, an inner insulator concentrically disposed about the inner conductor and an unbraided, solid outer conductor of minimal wall thickness integral with the outside surface of the inner insulator, said cables being further defined by the end portions of the inner insulator and outer conductor being trimmed back to expose the next lower, concentric layer; said assembly comprising:

(a) a metallic contact pin and a metallic contact receptacle coaxially secured to the respective inner conductors of the first and second cables, said contact pin having a solid end portion opposite the exposed end of the inner conductor, said contact receptacle having an axial bore which defines a continuously surfaced end portion opposite the exposed end of the second inner conductor, said contact pin and contact receptacle being adapted to mate with each other in the assembled condition;

(b) first and second insulating sleeves tightly disposed about at least a portion of each of the respective contact pin and contact receptacle of the first and second cables proximate the exposed ends thereof, said first insulating sleeve also having an enlarged, concentric bore spacedly disposed about a portion of said contact pin extending from the end of the first inner conductor, said second insulating sleeve being tightly disposed about the entire length of said contact receptacle, said first and second insulating sleeves having a substantially uniform, continuous outside diameter in the assembled condition, said insulating sleeves being provided with integral, internal shoulders adapted to restrain said contact pin

and contact receptacle from axial motion relative to their respective cables;

(c) first and second metallic sleeves coaxially secured to the respective outer conductors of the first and second cables;

(d) third and fourth metallic outer sleeves coaxially joined to said first and second metallic sleeves, respectively, each of said third and fourth metallic outer sleeves having a first axial bore which defines a continuously surfaced end portion coaxial with and opposite the trimmed-back ends of the respective first and second cable outer conductors, said fourth metallic sleeve having a second coaxial bore adapted to mate with the end portion of said third metallic sleeve whereby a substantially uniform outside diameter is provided in the assembled condition of said metallic sleeves; and

(e) annular retaining means adapted to releasably couple said first and second metallic sleeves upon axial motion of one of said metallic sleeves in the direction of the outer of said metallic sleeves.

2. A subminiature cable and conductor assembly comprising:

(a) first and second coaxial cables each of which has an inner conductor, an inner insulator concentrically disposed about said inner conductor and an unbraided, solid outer conductor of minimal wall thickness integral with the outside surface of said inner insulator, said cables being further defined by the end portions of said inner insulator and outer conductor being trimmed back to expose the next lower, concentric layer;

(b) a metallic contact pin and a metallic contact receptacle coaxially secured to the respective inner conductors of said first and second cables, said contact pin having a solid end portion opposite the exposed end of said inner conductor, said contact receptacle having an axial bore which defines a continuous surfaced end portion opposite the exposed end of said second inner conductor, said contact pin and contact receptacle being adapted to mate with each other in the assembled condition;

(c) first and second insulating sleeves tightly disposed about at least a portion of each of said respective contact pin and contact receptacle of said first and

5

second cables proximate the exposed ends thereof, said first insulating sleeve also having an enlarged, concentric bore spacially disposed about a portion of said first pin opposite the end of said first inner conductor, said second insulating sleeve being tightly disposed about the entire length of said contact receptacle, said first and second insulating sleeves having a substantially uniform, continuous outside diameter in the assembled condition, said insulating sleeves being provided with integral, internal shoulders adapted to restrain said contact pin and contact receptacle from axial motion relative to their respective cables;

(d) first and second metallic sleeves coaxially secured to said respective outer conductors of said first and second cables;

(e) third and fourth metallic outer sleeves coaxially joined to said first and second metallic sleeves, respectively, each of said third and fourth metallic sleeves having a first axial bore which defines a continuously surfaced end portion coaxial with end opposite the trimmed-back ends of said respective first and second cable outer conductors, said second metallic sleeve having a second coaxial bore adapted to mate with said end portion of said first metallic sleeve whereby a substantially uniform outside diameter is provided in the assembled condition of said metallic sleeves; and

(f) annular retaining means adapted to releasably couple said first and second metallic sleeves upon axial motion of one of said metallic sleeves in the direction of the other of said metallic sleeves.
